Primary Examiner — Katrina A Betton(74) *Attorney, Agent, or Firm* — Snell & Wilmer LLP.(57) **CLAIM**

The ornamental design for a truck wrap windshield and grille, as shown and described.

DESCRIPTION

FIG. 1 is a perspective view of a truck wrap windshield and grille;

FIG. 2 is a front view thereof;

FIG. 3 is a right side view thereof;

FIG. 4 is a left side view thereof; and,

FIG. 5 is a top view thereof.

The broken lines are included for the purpose of illustrating portions of the truck and form no part of the claimed design.
